UNITED STATES PATENT OFFICE.

JOHN HOLLEY MOON, OF PORTLAND, OREGON.

PROPELLING MECHANISM FOR BOATS.

1,177,433.

Specification of Letters Patent. Patented Mar. 28, 1916.

Application filed January 28, 1915. Serial No. 4,860.

To all whom it may concern:

Be it known that I, JOHN H. MOON, a citizen of the United States, residing at Portland, in the county of Multnomah and State 5 of Oregon, have invented certain new and useful Improvements in Propelling Mechanisms for Boats, of which the following is a specification.

This invention relates to an improvement 10 in boats, and more particularly to an improvement in the propelling mechanism of a vessel.

One of the principal objects of the invention is to provide an improved endless 15 propeller in the form generally of a chain having blades movable into different positions for acquiring the most advantageous results when moving through the water, said blades being adapted to automatically 20 assume the proper positions whether the chain be driven in forward or in reverse direction.

A further object of the invention is to provide a propelling mechanism including 25 an endless propeller chain and including novel and improved means for manually transmitting power to the chain.

Still another object of the invention is to provide an improved apparatus of the class 30 described which will be extremely simple, durable, efficient in operation and inexpensive to manufacture.

With these and other objects in view which will become apparent as the description proceeds, the invention resides in the construction, combination and arrangement of parts, 35 hereinafter more fully described and claimed, and illustrated in the accompanying drawing, in which like characters of reference indicate like parts throughout the several figures, of which—

Figure 1 represents a top plan view of a boat constructed according to my invention. Fig. 2 represents a vertical longitudinal sectional view taken on the plane indicated by the line 2—2 of Fig. 1 looking in the direction indicated by the arrows. Fig. 3 represents a vertical central longitudinal sectional view taken on the plane indicated by the line 45 3—3 of Fig. 1 looking in the direction indicated by the arrows. Fig. 4 represents a vertical sectional view taken through a section of the upper flight of the chain pro-

peller on the planes indicated by the line 4—4 of Fig. 5 looking in the direction indicated by the arrows. Fig. 5 represents a top plan view of a section of the upper flight of the propeller chain. Fig. 6 represents a fragmentary perspective view of a portion of the upper flight of the chain. Fig. 7 represents a fragmentary transverse sectional view taken on the plane indicated by the line 7—7 of Fig. 5 looking in the direction indicated by the arrows. Fig. 8 represents a fragmentary sectional view taken longitudinally through a portion of one of the chain members indicating an enlarged opening through which one of the pivotal pins of the blades extends, and Fig. 9 represents a fragmentary longitudinal sectional view 70 taken on the plane indicated by the line 9—9 of Fig. 1.

Referring more particularly to the drawing, 5 indicates generally the hull of a vessel having a well 6 disposed amidships and having a second well at 7 provided near the stern. The floor 8 of well 7 is inclined as shown, and extending transversely through this well is a shaft 9 on which a pair of driving sprocket wheels 10 are keyed. A 80 drum 11 is journaled transversely of the vessel within the well 6, and traveling over the sprocket wheels 10 and the drum 11 is an endless propeller chain 12. The upper flight of the chain is supported by a trough 13 85 which connects the two wells. As will be understood the trough and chain extend longitudinally of the vessel. The lower flight of the chain moves across that portion of the bottom of the hull indicated at 14, which lies 90 between the wells. Secured to the bottom on each side of the lower flight of the propeller chain is a keel 15. The keels are of a depth slightly greater than the thickness of the chain in order that said keels may extend 95 below said chain somewhat to prevent damage to the chain should the vessel run aground.

The shaft 9 is supported in a pair of bearings 16 in which are swiveled the rear 100 ends of screw bolts 17. These bolts are threaded through the bearings 18 which are carried by floor 8 of the rear well. The outer ends of the bolts are provided with handles 19 by means of which said bolts 105 might be turned in order to shift the driv-

ing sprocket wheels whereby to tighten or loosen the propeller chain.

Journalized transversely of the trough at the rear end thereof, is a shaft 20. The latter is carried by bearings 21 carried in the walls of well 7. On this shaft at each end thereof is keyed a larger and a smaller sprocket wheel 21 and 22 respectively. Over the larger sprockets 21 run endless drive chains 23. These chains also run over sprockets 24 carried upon shaft 9 outside of and adjacent the driving sprockets 10.

Midway the length of the trough, a shaft 25 is journaled. This shaft is carried in bearings 26 having screw bolts 27 swiveled therein. The screw bolts are threaded through bearings carried by brackets 28 secured to the opposite sides of trough 13. Handles 29 provided on these bolts serve as means whereby the bolts may be turned through the brackets in order to shift the position of the shaft 25. Near each end of the shaft is carried a pair of sprocket wheels 30 and 31 respectively. Endless chains 32 run over the sprockets 30 and the sprockets 22 carried by shaft 20. At the forward end of the trough a third shaft 33 is journaled, and this shaft carries at each end a sprocket 34. Endless chains 35 run over the sprockets 34 and the sprockets 31 on shaft 25. Means whereby shaft 33 may be shifted is provided, this means being similar to the same mechanism by which shafts 25 and 9 may be shifted, and is indicated generally at 36. At each end of shafts 20, 25 and 33 is provided a crank arm 37 by means of which the shafts and sprocket wheels carried by them may be manually operated. Through this transmission mechanism including the various shafts, sprocket wheels and driving chains, rotation is imparted to the driving sprocket wheels, and consequently to the endless propeller chain for moving the latter in the desired direction whereby to propel the vessel. Instead of employing the mechanisms shown for shifting the various shafts whereby to vary the tension of the chains I may use any other suitable means without departing from the spirit of the invention.

At suitable points within the vessel are secured stools or chairs 38 upon which persons may sit while operating the power transmission mechanism.

The propeller chain which I use is of peculiar construction, and comprises a plurality of links indicated generally at 39. The links each comprise a pair of side pieces 40 provided with central longitudinally extending openings 41. The links at their ends are pivoted upon the reduced ends of shafts or pins 42. Outside of the links on each end of the shafts are pivoted wheels or rollers 43 provided preferably with rubber or other suitable tires 44. The links are ar-

ranged so that the pieces forming alternate links are at their ends pivoted within the pieces forming the adjacent links, in the manner indicated.

Each pair of pieces 40 forming a link, carries a transversely disposed propeller blade 45. The blades are in the form of flat plates of metal disposed transversely of the chain and having their ends reduced as at 46. The width of the reduced blade ends is slightly less than the width of the openings 41 in the links, so that said blades may rock upon their lower edges in a manner to be hereinafter described. The opposite members 40 of consecutive links are provided with pairs of bars or studs 47 connected to the opposite edges of the opening 41. The members of each pair of bars or studs are set at an angle to each other and are spaced apart as indicated, and between them the reduced ends of the propeller blades extend. The link sections opposite the sections carrying the bars or studs are provided in their lower portions (with regard to the upper flight of the chain) with openings at 48, disposed midway the length of the links, through which pins 49 loosely extend. These pins also extend through the adjacent reduced ends of the propeller blades, and at their upper ends project through slots 50 provided in the upper portions of those links. The lower ends of pins 49 are provided with knobs 51, of a diameter greater than the diameter of openings 48, while the opposite ends of the pins may be provided with cotter pins or other suitable retaining elements. The knobs 51 co-operate with the enlarged openings through which the pins extend in substantially providing a universal or ball and socket joint, so that the pins are free to swing longitudinally of the links, the length of their swing being limited by the terminals of slots 50.

It will be noted that the sections 40 of the links are of such curvature as to conform with the curvature of the drum 11 and sprockets 10. The wheels or rollers 43 engage upon the trough and bottom respectively of the body and provide a bearing or carriage for the chain, so as to render its action exceedingly smooth and frictionless. The sprockets 10 as indicated are provided with teeth having substantially semicircular recesses in them so as to accommodate and engage with the wheels 43 whereby to drive the propeller chain.

The operation of the propeller chain may be briefly described as follows. Supposing the boat to be driven forwardly the links after running off of drum 11 engage with the water for forcing the boat along. Immediately upon their engagement with the water the propeller blades will be momentarily stopped as it were or rather will be shifted as far toward the forward ends of 130

the links, or those ends leaving the drum 11 last, as possible. This operation disposes the blades so that they rest at an angle or inclination with the vertical and 5 against the bars 47 at the ends of the links toward the front of the boat. By having the pins 49 disposed centrally of the links, and by providing the slot and enlarged opening, the blades will rock into position 10 to engage against the bar 47 as set forth. However, the ends of the blades opposite the ends through which the pins 49 extend will not be in transverse alinement with their last said ends but they will be inclined 15 slightly or more properly disposed at an angle to the transverse central line of the links. This construction provides for a most advantageous position of the blades during their course through the water by 20 allowing the water to slide off of the blades in the proper manner without becoming backed up upon them as would be the case were the blades fixed in a vertical and transverse plane.

25 The pivot points of the consecutive blades are as noted disposed alternately on opposite sides of the chain throughout its length, so that the action of some of the blades in shifting the water laterally and downwardly 30 with respect to the chain will be counteracted and equalized by the remaining blades. Upon reversing the direction of rotation or travel of the chain, the blades will immediately be shifted to a position directly opposite 35 site that described, the same result being obtained namely, proper engagement with the water for shifting the same somewhat laterally and downwardly so as to prevent backing up against the blades.

40 Suitable means is provided whereby the boat may be properly steered. This includes a rudder 55 pivotally hung at the stern of the boat, and suitable mechanism indicated at 56, mounted in any convenient 45 manner, whereby the rudder may be operated.

Although I have described the preferred embodiment of my invention, I may desire to make such changes in the construction, 50 combination and arrangement of parts thereof as do not depart from the spirit of the invention and the scope of the appended claims.

I claim:—

55 1. A boat including a propelling mechanism, said mechanism including an endless chain formed of a plurality of hingedly connected links, said links each comprising a pair of members provided with central openings, blades carried by each link and having reduced ends extending through the openings of the opposite link members, said reduced ends being loosely disposed within said openings, studs carried by one 60 of the members of each link, said studs be-

ing disposed at an angle to and in spaced relation to each other and adapted to limit the movement of the adjacent reduced end of the blade, a pin carried by the opposite link section and extending loosely through 70 an opening in one side of the section and into a slot provided in the opposite side of the section, said pin adapted to also extend through the opposite reduced blade end, means for preventing accidental loss of the 75 pin, the pins being disposed on opposite sides of the adjacent consecutive links in the chain, substantially as described.

2. In a propeller chain, a link comprising a pair of opposite sections having central 80 longitudinally extending openings, a blade disposed between the sections and having reduced ends loosely extending into said openings, said blade being movable upon contact with the water, means for limiting 85 the movement of the blade in either direction, said blade adapted upon contact with the water to be moved into such position as to shift water laterally and downwardly 90 whereby to prevent backing of water against the blade.

3. In a propeller chain, a plurality of hingedly connected links, blades loosely carried by the links transversely thereof and adapted upon engagement with the water 95 to be moved in one direction or another, means carried by the links for limiting the movement of the blades, said blades adapted upon engagement with the water to be shifted into such position as to provide for 100 the lateral and downward shifting of the water over the blades, the alternate blades being pivotally supported upon opposite sides of the chain, whereby the lateral shifting of the water by certain of the blades will 105 be counteracted by the others.

4. A propeller chain including a plurality of links, each link comprising opposite sections, a shaft on which the adjacent link sections are pivotally disposed, blades 110 carried by the links, means for mounting the blades whereby they may be shifted upon engagement with the water into such position as to provide for the downward and lateral shifting of the water over the 115 blades, and wheels carried by the shafts on the outside of the links and adapted to form a carriage and bearing for them.

5. An endless propeller chain adapted to be moved through the water for propelling 120 a boat, said chain including a plurality of blades, means for mounting the blades whereby they may be swung bodily in one direction or another upon engagement with the water, and means for limiting the 125 movement of said blades whereby to dispose the blades at such angles as to provide for the lateral and downward shifting of the water over them.

6. An endless propeller chain adapted to 130

be moved through the water for propelling a boat, said chain including a plurality of movable blades adapted to be shifted in one direction or another upon engagement with the water, and means for limiting the movement of the blades for retaining them in such positions as to provide for a lateral

and downward shifting of the water over the blades.
